UNITED STATES PATENT OFFICE.

JOHN HAYES, OF AMSTERDAM, NEW YORK, ASSIGNOR TO UNION SPECIAL MACHINE COMPANY, OF CHICAGO, ILLINOIS, A CORPORATION OF ILLINOIS.

SEWING-MACHINE.

1,216,687.

Specification of Letters Patent. Patented Feb. 20, 1917.

Application filed October 7, 1910. Serial No. 585,790.

To all whom it may concern:

Be it known that I, JOHN HAYES, a citizen of the United States, residing at Amsterdam, in the county of Montgomery, State of New York, have invented certain new and useful Improvements in Sewing-Machines, of which the following is a description, reference being had to the accompanying drawing and to the letters and figures of reference marked thereon.

The present invention relates to new and useful improvements in sewing machines, and more especially to the feeding mechanism of a sewing machine.

15 The invention as herein shown is especially adapted to machines of the character which operate to full or gather a piece of fabric prior to stitching the same; or full or gather one piece of fabric relative to another, and secure the same together.

20 When placing a binding strip or the like upon a knitted fabric, and more especially when binding across the wales of a knitted fabric, the knitted fabric is very apt to become stretched or distorted in the stitching operation. By my improved mechanism, the knitted fabric may be fed slightly faster than the binding strip or non-elastic material, thus overcoming the tendency of the 25 knitted fabric to stretch so that the two pieces of fabric will be evenly and smoothly stitched together.

30 It is sometimes desirable when stitching one piece of fabric to another of the above character, to cause the fulling action of the feeding mechanism to cease, as for example, when crossing stay strips and the like; and the invention, therefore, contemplates providing mechanism whereby the fulling action 35 of the feeding mechanism may be rendered ineffective whenever desired, without stopping the stitching mechanism.

35 Machines of the character to which this invention relates are usually known in the trade as collaret machines, and are used for binding the collar or neck opening of knitted underwear, the binding strip being of different material from that of the garment itself. A differential feed mechanism is usually a part of such machines, that is, a two-motion feed, in which the feed dog in front of the needle moves at a different rate of speed from the other part, and crowds in, fulls or gathers the fabric which it engages.

50 It is the object of my invention to pro-

vide a mechanism by which the effective or ineffective action of the front feed dog may be controlled at the will of the operator, preferably the normal action of the parts being to cause the feeding mechanism to work 60 differentially, the forward feed dog being thrown out of effective relation to the fabric whenever desired, especially when crossing the button stay strips or front facings of the garment.

55 The invention, therefore, consists in the matters hereinafter described and referred to in the appended claims.

The invention is illustrated in the accompanying drawings, in which,—

65 Figure 1 is a plan view of the cloth plate and presser foot of a sewing machine, part of the throat plate and presser foot being removed, the presser bar shown in section, and the binding guide and folder being shown in position;

70 Fig. 2 is an end view, partly in section, of a portion of a sewing machine embodying my invention, both feeds being shown depressed, the forward feed being shown in effective position, with respect to coöperation with the rear feed;

75 Fig. 3 is a similar view, showing both feed dogs raised and operating on the fabric;

80 Fig. 4 is a detail view of the feed dogs and the means for throwing the forward dog into and out of operation, the two positions thereof being shown respectively in dotted and full lines;

85 Fig. 5 is a plan view of the feeding mechanism;

90 Fig. 6 is a detail view of the support for the forward feed dog, being a section on line 6—6 of Fig. 5;

95 Fig. 7 is a detail view of the treadle-controlled lever which operates the forward feed dog; and

100 Fig. 8 is a view of the treadle and a chain and the lever connected to said chain.

105 In these drawings I have shown a portion of a sewing machine of the well known Union Special type, the bed plate being shown at 1, the cloth plate at 2, the throat plate at 3, the needle at 4, the presser bar at 5, the main shaft at 6, and the feed-operating eccentric at 7, these parts being of well known construction and not necessary to be more particularly described.

110 The feeding mechanism consists of the main feed dog 8^a and auxiliary feed dog 9.

The main feed dog has three sets of serrations 8, 10 and 11, the forward ones of the serrations 8 extending to the front alongside the needle, the serrations 10 being in rear of said needle, and the serration 11 being in rear and to one side of the needle. The main feed dog, indicated at F in Fig. 5, is secured to the forward end of the feed bar 9^a by screws f, f, which pass through slots f', f'. These slots permit the feed dog to be adjusted transversely of the line of feed. The supplementary presser foot 12, coöperates with serrations 10 and 11, and the main foot 13 with serration 8 and with the serrations on auxiliary feed dog 9.

The main feed dog serrations 8 and auxiliary feed dog 9 act upon the main or body fabric, the auxiliary feed dog entirely so, to feed it up to the needle and since it has a differential movement with respect to the main feed dog it crowds or fulls or gathers the goods ahead of the needle. The serrations 10 act upon that portion of the goods which has been stitched together, and the serrations 11 on the binding, which is guided and folded around the edge of the body or knit goods by the folding guides 14 and 15.

The main feed dog 8^a is carried by a feed bar 9^a which is pivotally attached to a rod 10^a, carried by a feed rocker 11^a, which feed rocker is oscillated by the usual well known means of a crank on the forward end of the main shaft 6. As the feed rocker oscillates, the main feed bar will be moved back and forth carrying with it the main feed dog 8^a. The eccentric 7, above referred to, gives a rising and falling movement to this feed bar. The auxiliary feed dog 9 is carried by an auxiliary feed bar 16, which is mounted so as to slide back and forth on the main feed bar. The main feed bar carries a plate on which this auxiliary feed bar rests and a retaining plate 12^a, secured to the main feed bar 9^a, by screws 13^a, extends over the auxiliary feed bar 16, as clearly shown in the drawings and retains the same on the supporting plate, so that it may be reciprocated back and forth freely on the main feed bar and move up and down bodily with the main feed bar, through the action of the eccentric 7 on said main feed bar. The auxiliary feed bar 16 is provided with a lug 26. A link 27 pivoted to this lug has an adjustable connection through a bolt 14^a with a slot 15^a in an arm 16^a carried by the feed rocker 11^a. The connection between the link 27 and the feed rocker is at a different point than the rod 10^a, which serves as the pivotal connection between the main feed bar and the feed rocker, and, therefore, a differential movement is imparted to the auxiliary feed bar.

Upon the forward end of the auxiliary feed bar 16 is formed or attached a head 17, having a socket 18 forming a seat for a spring

19, attached at one end to the plate or bar 20, which carries the feed dog 9. Said bar 20 has also a downwardly extending flattened portion 21, dovetailed in a groove 22 in the head 17, and projecting through said head is 70 engaged by the forward end of a lever 23, pivoted at 24 to an extension 25 of the lug 26 on the auxiliary feed bar, to which lug the pivotal link 27 is attached to impart the differential movement to the auxiliary feed 75 bar. This lever partakes of the rising and falling and forward and backward movements of the auxiliary feed bar, and the spring 19 keeps the feed dog 9 in position of normal action, at the usual times, on the 80 fabric.

It will be noticed from the arrangement of parts that when the rear end of the lever 23 is raised, the forward end will draw down on the part 21 and draw the feed dog 85 9 out of effective engagement with the fabric, thus causing all the work of feeding to be performed by the main feed dog.

In the class of machines to which this invention relates, it is desirable to dispense 90 with the operative action of the differential or auxiliary feed dog, when crossing facings or stay strips, and it is desirable to place it under ready control of the operator. For this purpose I pivot at the back of the machine, to the bed plate 1, at 28, a lever 29, to which at one end is attached a chain 30 connected to the usual spring treadle 31 on the floor, or to a knee piece controlled by the operator, and the opposite end 32 extends 100 beneath the rear end of the lever 23, so that when the end 32 is raised by drawing down the opposite end, it will force up the rear end of lever 23 and draw down the feed dog 9. Upon the release of the lever 29, it will 105 return to normal position, and allow the spring 19 to return the feed dog 9 to operative position.

The lever 23 partaking as it does of the movements of the auxiliary feed bar even 110 when the dog 9 is out of engagement with the work, that is, when the end 32 of lever 29 is forcing upward the rear end of said lever 23, the parts of the two levers in contact are so made as to minimize friction and 115 wear. The said lever 23 has a sliding contact with the lever 29. The upper end of a rib 33 on part 21 extends beneath the main feed dog and limits the upward movement of the auxiliary feed dog. (See Fig. 5.) 120

Having thus particularly described my invention, what I claim as new and desire to secure by Letters Patent is:—

1. A fabric-feeding mechanism for sewing machines, including a main feed device, an auxiliary feed device carried thereby with means for imparting to the latter differential movement with respect to the former, and means under the control of the operator for moving said auxiliary device from operative 130

to inoperative position while the machine is in operation.

2. A fabric feeding mechanism for sewing machines, comprising a main feed bar and feed dog carried thereby, an auxiliary feed bar, and means for reciprocating both feed bars, a feed dog vertically movable on the auxiliary feed bar, and means under the control of the operator for moving said feed dog from operative to inoperative position without stopping or retarding the action of the machine.

3. A fabric feeding mechanism for sewing machines, comprising a main feed bar and feed dog carried thereby, an auxiliary feed dog bar and a feed dog, spring-supported thereon in normally operative position, and means under the control of the operator for moving said feed dog from operative to inoperative position, without stopping or retarding the action of the machine.

4. A fabric feeding mechanism for sewing machines, comprising feeding devices and means for moving them differentially, one of said feeding devices including a carrier, a feed dog thereon, said feed dog being vertically movable on its carrier and normally held in position to effectively engage the fabric, means under the control of the operator to impart said vertical movement thereto, to withdraw it from effective engagement with the fabric without varying its stroke and without stopping or retarding the action of the machine.

5. A fabric feeding mechanism for sewing machines, comprising feeding devices and means for moving them differentially, one of said feeding devices including a vertically movable feed dog with a spring for keeping it normally raised, and means under the control of the operator to lower it against the pressure of the spring without stopping or retarding the action of the machine.

6. A fabric feeding mechanism for sewing machines comprising a main feed dog, an auxiliary feed dog supporting bar with a feed dog thereon in advance of the main feed dog, with means for moving the said auxiliary feed dog differentially with respect to the former, means for raising and lowering the auxiliary feed dog bodily, said means including a lever engaging at one end said auxiliary feed dog and pivoted to the auxiliary feed dog supporting bar, and means under the control of the operator adapted at will, to be brought into engagement with said pivoted lever to impart bodily movement to said auxiliary feed dog.

7. A fabric feeding mechanism for sewing machines, comprising a main feed dog, an auxiliary feed dog supporting bar with a feed dog thereon in advance of the main feed dog, means for moving the said auxiliary feed dog differentially with respect to

the former, means for raising and lowering the auxiliary feed dog bodily, said means including a lever engaging at one end said auxiliary feed dog and pivoted to the auxiliary feed dog-supporting bar, means under the control of the operator adapted at will to be brought into engagement with said pivoted lever to impart bodily movement in one direction to said auxiliary feed dog, and a spring for moving said lever in the opposite direction.

8. A fabric feeding mechanism for sewing machines, comprising a main feed dog, and an auxiliary feed dog in advance thereof with means for moving the latter differentially with respect to the former, means for raising and lowering the auxiliary feed dog bodily, said means including a pivoted lever engaging at one end said auxiliary feed dog, means under the control of the operator adapted at will to be brought into engagement with said pivoted lever to impart bodily movements to said auxiliary feed dog, including a second pivoted lever arranged at right angles to said pivoted lever, and adapted to engage at one end the rear end thereof.

9. A fabric feeding mechanism for sewing machines, comprising a main feed dog, and an auxiliary feed dog in advance thereof with means for moving the latter differentially with respect to the former, means for raising and lowering the auxiliary feed dog bodily, said means including a pivoted lever engaging at one end said auxiliary feed dog, means under the control of the operator adapted at will to be brought into engagement with said pivoted lever to impart bodily movement to said auxiliary feed dog, a second pivoted lever arranged at right angles to said pivoted lever and adapted to engage at one end the rear end thereof, and a spring for returning said feed dog to normal position.

10. In a feeding mechanism for sewing machines, a main feed bar, an auxiliary feed bar, feed dogs carried by said main and auxiliary feed bars, means to impart work feeding movements to said main and auxiliary feed bars, and means whereby one of said feed dogs can be given a bodily vertical movement with respect to its carrying bar to withdraw it from effective engagement with the fabric, without varying its stroke and without stopping or retarding the action of the machine.

11. A fabric feeding mechanism for sewing machines including a feed bar, a head carried thereby having a groove formed therein, a feed dog having a shank engaging said groove and adapted to move vertically therein, said head having a socket, a spring supported in said socket and engaging the feed dog and operating normally to hold said feed dog raised, and means operating to

lower said feed dog against the action of said spring.

12. A fabric feeding mechanism for sewing machines, including a main feed bar, a feed dog carried thereby, an auxiliary feed bar, a vertically movable feed dog thereon, said vertically movable feed dog carrying a projection adapted to engage the under side of the main feed dog to limit the vertical movement of said auxiliary feed dog.

13. A feeding mechanism for sewing machines, including a main feed and an auxiliary feed, said main feed and auxiliary feed being arranged one in advance of the other, and having their work engaging surfaces in substantially the same horizontal plane, means whereby said auxiliary feed is given a differential movement with respect to the main feed, means for giving the two feeds a rise and fall in unison, and means whereby said auxiliary feed may be drawn out of the horizontal plane passing through the fabric engaging surface of the main and auxiliary feeds, without stopping or retarding the action of said feed device.

14. A feeding mechanism for sewing machines, including a main feed dog and an auxiliary feed dog, said main feed dog and auxiliary feed dog being arranged one in advance of the other and having their work engaging surfaces in substantially the same horizontal plane, means whereby said aux-

iliary feed dog is given a differential movement with respect to the main feed dog, and means whereby said auxiliary feed dog may be drawn out of the horizontal plane passing through the fabric engaging surface of the main and auxiliary feed dogs without stopping or retarding the action of said feed device, and means for automatically restoring said auxiliary feed dog to normal position.

15. A fabric feeding mechanism for sewing machines, comprising a main feed and an auxiliary feed, with connections between the same for imparting a common rise and fall, and differential forward and backward movements thereto, said auxiliary feed including a feed dog having bodily vertical movement out of the range of the fabric, independent of the rising and falling movements common to both feeds, whereby said auxiliary feed may be bodily withdrawn from effective coöperation with the fabric and means for moving the auxiliary feed dog bodily vertically out of range of the fabric without stopping the action of the feeding mechanism.

In testimony whereof I affix my signature, in presence of two witnesses.

JOHN HAYES.
